SKI-SCOOTER OR SIMILAR ARTICLE

Theodore P. Nelson, Portland, Mich.

Application March 24, 1955, Serial No. 35,182

Term of patent 7 years

(Cl. D34—15)

Figure 1 is a top front perspective view of a ski-scooter or similar article embodying my new design;

Figure 2 is a top rear perspective view; and

Fig. 3 is a side elevational view thereof, to a reduced scale, portions thereof being omitted for convenience of illustration.

I claim:

The ornamental design for a ski-scooter or similar article, as shown and described.
